CLAIM

The ornamental design for a cordless lopper, as shown and described.

DESCRIPTION

FIG. 1 is a perspective view of a cordless lopper showing my new design with jaws open.

FIG. 2 is a left side view of a cordless lopper according to FIG. 1.

FIG. 3 is a right side view of a cordless lopper according to FIG. 1.

FIG. 4 is a front view of a cordless lopper according to FIG. 1.

FIG. 5 is a rear view of a cordless lopper according to FIG. 1.

FIG. 6 is a top view of a cordless lopper according to FIG. 1.

FIG. 7 is a bottom view of a cordless lopper according to FIG. 1.

FIG. 8 is a perspective view of a cordless lopper showing my new design with jaws closed.

FIG. 9 is a left side view of a cordless lopper according to FIG. 8.

FIG. 10 is a right side view of a cordless lopper according to FIG. 8.

FIG. 11 is a front view of a cordless lopper according to FIG. 8.

FIG. 12 is a rear view of a cordless lopper according to FIG. 8.

FIG. 13 is a top view of a cordless lopper according to FIG. 8; and,

FIG. 14 is a bottom view of a cordless lopper according to FIG. 8.

The broken lines shown in the drawings represent unclaimed portions of the cordless lopper and form no part of the claimed design.
